UNITED STATES PATENT OFFICE.

JAMES DUNLOP, OF MANCHESTER, ENGLAND, ASSIGNOR TO CHARLES HENRY SCHILL, OF SAME PLACE.

PNEUMATIC HAMMER.

SPECIFICATION forming part of Letters Patent No. 672,638, dated April 23, 1901.

Application filed February 26, 1901. Serial No. 48,951. (No model.)

To all whom it may concern:

Be it known that I, JAMES DUNLOP, engineer, a subject of the King of Great Britain, residing at 206 Gorton Lane, Gorton, Manchester, in the county of Lancaster, England, have invented certain new and useful Improvements in Pneumatic and Like Percussive Hammers, of which the following is a specification.

- 10 This invention relates to pneumatic and like percussive hammers of the differential-piston inertia-valve type, and has for its object an improved construction of the inertia-valve and air-passages whereby the action 15 of the valve in distributing the compressed air or other motive fluid will be rendered more certain and the resulting action of the hammer itself be such that very little jarring or vibration will take place.
- 20 Hitherto the use of inertia-valves in pneumatic and like percussive hammers has resulted in faulty and uncertain action, owing to the excessive rebound of the valve from its terminal stops at either end of its travel, 25 and consequently an objectionable amount of jarring and vibration has taken place.

The means taken to prevent unnecessary or excessive rebounding of the inertia-valve and the improved construction and arrangement of parts necessary therefor constitute 30 the chief features of this invention.

In the accompanying drawings, Figure 1 is a longitudinal sectional elevation of the improved pneumatic or like percussive hammer adapted for use as a hand-tool. Fig. 2 is a similar view, but showing the parts in the relative positions they occupy when the piston has reached the other end of its stroke.

In the views, A designates the barrel or 40 cylindrical body of the hammer, and B a differential piston fitted to slide therein. The annular space C formed by the difference in the two diameters of the piston B is supplied with compressed air or other motive fluid, at 45 such times as it is desired to work the hammer, through a passage D, drilled in the body A and communicating with a starting-valve E, placed in the handle F.

The handle F is secured to the body A by 50 means of a screwed collar G, mounted loosely on the body, and when screwed up the parts

are locked together by teeth on a spring-catch I, engaging a ring of teeth formed on the collar G.

The compressed air or other motive fluid 55 is supplied to the handle F through a flexible pipe (not shown) attached to the nozzle H, and the starting-valve E is opened when required against the pressure of the motive fluid by the operator depressing the trigger- 60 lever J with his thumb.

Within the piston B is drilled a valve-race K, in which is fitted with a sliding fit a hollow inertia piston-valve L, having fitting parts at such a distance apart as to cover and 65 uncover almost simultaneously the two rows of holes M and N, drilled through the smaller diameter of the piston B. That part of the inertia-valve L which lies between the fitting parts has holes O drilled through it, and 70 at the end of the valve farthest away from the handle F a very small hole P is drilled. A plug Q is screwed into the end of the piston B, and this plug limits the travel of the inertia-valve L toward that end of the piston, the 75 travel toward the other end being limited by the opposing wall of the small chamber R. (See Fig. 1.)

On the end of the piston B is a projection S for striking any tool placed in the tool-socket 80 T, and between the tool-socket T and that part of the barrel A which fits the smaller diameter of the piston B is a chamber U, communicating with the atmosphere through the exhaust-ports V.

The action of the parts is as follows: The motive fluid admitted by depressing the trigger J and opening the valve E flows through the passage D into the annular space C and pressing on the annular area of the piston B 90 tends to move it into the position shown in Fig. 1. In this position and with the inertia-valve L in the position there shown the motive fluid will pass from the annular space C through the holes N and O to the space be- 95 hind the larger end of the piston, and there, acting on its full area, will drive it into the position shown in Fig. 2, where the projection S is shown in contact with a tool in the tool-socket T, the blow having been delivered 100 and the motion of the piston arrested. When the motion of the piston is thus suddenly ar-

rested, the momentum of the inertia-valve L will carry it also into the position shown in Fig. 2 or into an approximate position. In moving into this position the valve L will 5 compress the motive fluid in the small chamber R to a higher pressure than that acting on the larger end of the piston, and thus prevent the valve L from striking violently against the opposing wall of the chamber R, 10 and so obviate jarring, as well as excessive rebound of the valve, as the compressed fluid can escape gradually through the small hole P. When the inertia-valve L has moved into the position shown in Fig. 2, communication 15 between the annular space C and the space behind the larger end of the piston B is cut off by the fitting part of the valve L covering the holes N and communication between the atmosphere, and the space behind the 20 larger end of the piston is established by the other fitting part of the valve L uncovering the holes M. The exhaust of the motive fluid now takes place through the holes O and M, chamber U, and ports V. When the fluid pressure in the space behind the larger end 25 of the piston B is sufficiently reduced, the motive fluid, acting on the annular area of the piston, will again move it into the position shown in Fig. 1, and during that movement 30 the holes M in the smaller part of the piston B will pass into the fitting part of the barrel A, and thereby communication between the atmosphere and the space behind the larger end of the piston will be cut off. The motive 35 fluid remaining in the space behind the larger end of the piston B will then be compressed during the remainder of the stroke until the piston is brought to a stop in the position shown in Fig. 1. Just previous to reaching that position the holes M will pass into the annular space C and motive fluid will flow through the holes M and O and acting on the full area of the piston B will suddenly arrest its motion 40 and then drive it back on the reverse stroke 45 already described. The motion of the piston B being thus suddenly arrested the momentum of the inertia-valve L will carry it also into the position shown in Fig. 1, thus cutting off communication through the holes M 50 and establishing communication through the holes N as before. In moving into this posi-

tion the valve L will cause a slight reduction of fluid-pressure in the small chamber R, and this prevents the valve L from striking violently against the plug Q and so prevents any 55 excessive rebound. The hammer will continue working as described so long as the thumb of the operator remains pressing down the trigger J and motive fluid continues to enter through the starting-valve E. 60

Having now particularly described and ascertained the nature of my said invention and in what manner the same is to be performed, I declare that what I claim is—

1. In a pneumatic or like percussive hammer, in combination, a barrel or cylindrical body provided with passages for the supply of motive fluid under pressure, a differential piston fitted to slide therein, an annular space formed by the difference in the two diameters 65 of the piston, a hollow inertia piston-valve fitted inside the piston, and having fitting parts at each end adapted to alternately cover and uncover almost simultaneously two sets of holes in the smaller diameter of the piston, 70 the said inertia-valve having a set of holes between its fitting ends communicating with the space between it and the piston, and a single small hole in its end communicating with a small chamber formed between the 75 valve and the interior of the striking end of the piston, and an enlarged chamber with exhaust-ports beyond that part of the barrel which fits the smaller diameter of the piston, all arranged and operating substantially as 80 85 and for the purposes herein described with reference to the drawings.

2. In a pneumatic or like percussive hammer having a barrel fitted with a differential piston, the combination with the inertia-valve 90 L provided with a small hole P, of the chamber R and the motive-fluid passages and ports forming a fluid-pressure check at each end of the traverse of the inertia - valve substantially as herein set forth. 95

In witness whereof I have hereunto set my hand in presence of two witnesses.

JAMES DUNLOP.
